DRILLING MECHANISM.

Application filed October 3, 1923. Serial No. 668,295.

This invention particularly pertains to a mechanism for drilling holes in the earth, as in for oil, gas, or water, forming bore holes in search of minerals or to ascertain the 5 nature of underlying strata, in driving shafts in mining operations, etc.

An object of this invention is to provide a drilling mechanism which is especially adapted for forming holes of large diameter 10 to great depth, such for example as holes measuring two or three feet across and of several thousand feet in length.

Another object is to provide a drilling mechanism which is so constructed and 15 operated as to insure the formation of a straight bore to a great depth, effect rapid penetration, and afford economy in time, labor and expense by facilitating the withdrawal of the cutting tools from the bore 20 and their replacement therein when it becomes necessary so to do, as for sharpening and repairing the tool.

Another object is to provide a drilling mechanism in which cutting tools may be 25 actuated by fluid pressure, such as compressed air, and to provide a means whereby the fluid pressure may be delivered to and exhausted from the tool-actuating mechanism in such manner that the tools may be 30 operated when disposed at the bottom of a deep bore and submerged in liquid under pressure.

Another object is to provide a drilling mechanism of the above character which 35 possesses the following parts and features, to-wit:

First—A tubular revoluble stem adapted 40 to be lowered into a well and through which liquid may be passed;

Second—A removable head adapted to be 45 raised and lowered relative to the stem and to be detachably interconnected with the stem when disposed at the lower end portion thereof so as to be supported on the stem and be revoluble therewith.

Third—Fluid pressure operated tools carried by the head adapted to be moved in and out of an operative position as the head is moved into and away from its interconnection with the stem; so that the head may be 50 freely raised and lowered in a well casing or bore with the tools disposed clear of the walls thereof and whereby the tools will be extended when the head is engaged with the stem so as to project across the peripheral

plane of the head to cut a bore of a diameter larger than that of the head;

Fourth—Means whereby fluid pressure may be delivered to and exhausted from the tool operating mechanism when the head and stem are interconnected, the fluid for operating the tools passing through separate conduits located in the stem whereby the tools may be actuated in wells containing liquid under high pressure thereby enabling drilling wells 60 of great depth by compressed air operated cutting tools; and embodying a construction whereby the head may be withdrawn from the bore and replaced therein without necessitating withdrawing and replacing the fluid 65 pressure conduits.

Fifth—Valve controlled means for controlling communication between the fluid pressure supply and exhaust conduits in the stem, and the tool operating mechanism on 70 the head when the head and stem are interconnected, adapted to close the communication when the head is out of interconnection with the stem so as to prevent liquid 75 in the well from entering the fluid pressure 80 chambers in the head and stem when the head is being raised or lowered relative to the stem; and

Sixth—Means for maintaining the fluid pressure actuated parts thoroughly lubricated during their operation while submerged. 85

A further object is to provide a construction whereby the parts may be readily assembled or disassociated.

With the foregoing objects in view together 90 with such other objects and advantages as may subsequently appear, the invention resides in the parts, and in the construction, combination and arrangement of parts or 95 their equivalents, hereinafter described and claimed and illustrated by way of example in the accompanying drawings, in which:—

Fig. 1 is a view of the drilling mechanism as seen in side elevation showing the tool carrying head and the stem as interconnected and the parts disposed in their drilling position. 100

Fig. 2 is a view in transverse section as seen on the line 2—2 of Fig. 1.

Fig. 3 is a perspective view of the lower 105 end portion of the stem with parts broken away.

Fig. 4 is a perspective view of the cutting tool.

Fig. 5 is a view in elevation, partly in 110

transverse section, of the head as detached from the stem.

Fig. 6 is a horizontal section and plan view as seen on the line 6—6 of Fig. 2.

Fig. 7 is a view in section as seen on the line 7—7 of Fig. 2.

Fig. 8 is a view in section as seen on the line 8—8 of Fig. 2.

Fig. 9 is a view in extended transverse section as seen on the line 9—9 of Fig. 6, parts being shown in elevation.

Fig. 10 is a plan view of the lower end of the drilling mechanism, with the parts disposed in the cutting position as shown in Fig. 1.

Fig. 11 is a detail in section and elevation as seen substantially on the line 11 of Fig. 6, showing the stem valves for closing the communication between the fluid pressure chambers in the head and stem.

Fig. 12 is a detail in section as seen on the line 12 of Fig. 7, illustrating the exhaust drain.

More specifically 14 indicates a tubular stem which embodies a series of joined pipe sections 15 (as is common in well drilling machinery) and a tubular end section 16; the stem being adapted to be lowered into a bore and rotated in the usual manner, it being also connected to a suitable pump not shown by which water is delivered through the stem to the bore to maintain such flow of water as to carry off the detritus formed in the drilling operation. A peripheral flange 17 is formed adjacent the lower end of the stem portion 16 which flange is provided with a series of depressions or scallops 18 as shown in Figure 3, and projecting from the sides of the stem are longitudinal ribs 19 leading from the scallops 18 which ribs are formed with inclined or spiral teeth 20.

Formed interiorly of the stem is a pair of separate chambers 21 and 22 (shown in Figures 2 and 9) which chambers have ports 23 and 24 respectively which lead through the wall of the stem. Arranged to extend over the ports 23 and 24 is a slid able sleeve valve 25 having ports 26 and 27 adapted to be disposed to register with the ports 23 and

24. Disposed in recesses 28 in the outer face of the stem are springs 29 which bear between an end wall of the recess and a connection 30 on sleeve 25 to normally maintain the sleeve in its upper or port closing position. Connecting with the chamber 21 is a conduit 31 which leads upward through the stem and communicates with any suitable source of fluid pressure supply and serves as a means of conveying fluid under pressure to the lower end portion of the stem. Connecting with the chamber 22 is a conduit 32 which leads upward through the conduit 31 and serves as an exhaust for the fluid pressure after the same has been employed in operation of the cutting tools as

will be later described. The conduits 31 and 32 thus affords separate passages for the intake and exhaust of the fluid pressure and are enclosed from liquid in the stem and the bore.

33 indicates a tool carrying head which is of general cylindrical tubular form and is adapted to be positioned to encompass the stem 15 and is so designed that it may be raised and lowered relative to the stem; the head being provided at its upper end with a flange 34 adapted to be engaged by a suitable tool affixed to a cable by which the head may be raised and lowered; the head engaging tool and its operating mechanism being of any well known construction in devices of this character and accordingly not necessary to be here shown.

The head is designed to be carried by and interconnected with the lower end portion of the stem and is accordingly formed of such inside diameter adjacent its lower end as to seat on projecting portions of the flange 17 as shown in Figure 9; there being projecting collars 35 on the lower end of the head which are adapted to extend into the scallops 18 of the flange 17 to form a splined connection between the stem and head whereby on rotation of the stem the head will turn therewith.

Carried by the head is a series of cutting tools 36 each of which embodies a suitable blade 37 mounted on a shank 38 and extending at right angles to the axis of the latter; the shank extending through a collar 35 into a recess in the lower portion of the head 33 and being reciprocally and turnably mounted. The shanks extend parallel to the axis of the head and have their upper end portions splined in engagement with rings 39 formed with inclined teeth or projections 40 adapted to be engaged with the inclined teeth 20 on the stem whereby the shanks 38 carrying the blades 37 may be turned a partial revolution on moving the head in and out of its interconnected position on the stem. A spring 41 surrounding the stem acts to maintain the latter in its uppermost position.

Within the head above each shank 38 is a fluid pressure operated mechanism of the type commonly employed in compressed air operated tools; this mechanism being here shown as embodying a piston 42 carried in a cylinder 43 and having a piston rod 44 adapted to impact on the end of the tool shank on reciprocation of the piston to impart a downward movement of the cutting tool in opposition to the spring 41.

Means are provided for affording a communication between the ports 23—26 and 24—27 and the cylinder 43 when the head is disposed in its interconnected position on the stem. This means embodies an intake passage 45 and an exhaust passage 46 which

open to the interior of the head through ports 47 and 48 adapted to register with the ports 26 and 27 in the sleeve valve 25. A suitable valve control mechanism is disposed 5 in a recess 49 adjacent to each cylinder 43 to cooperate with the piston 42 in effecting operation of the latter as is common in compressed air tool construction.

Means are provided for normally closing 10 the ports 47 and 48 when the head is out of its interconnected position on the stem so as to prevent ingress of water or liquid from the well into the air chambers of the fluid pressure operated mechanism. This means 15 is here shown as embodying an internal sleeve valve 50 carried on the head 33; there being springs 51 disposed in recesses in the head bearing between the end walls of the recesses and a connection 52 on the sleeve 50 20 (as shown in Figure 11) to normally maintain the sleeve in its downward or port closing position. The sleeve 50 is arranged to align with the sleeve 25 and is situated so that when the head is lowered into its seated position on the stem the lower edge 25 of the sleeve 50 will abut against the upper edge of sleeve 25 and act to depress the latter in opposition to the springs 29 and thereby open the communication between the 30 air intake and exhaust chambers in the stem to the fluid pressure operated mechanism in the head through the ports 23 and 24; there being a movement of sleeve 50 coincident with movement of the sleeve 29 to move the sleeve 50 from in front of the ports 47 and 48 and thereby open the latter.

Formed in the head 33 is a lubricant containing chamber 55 (shown in Figure 9) communicating through a passage 56 with the chamber 57 into which the tool shank projects for the purpose of delivering a lubricating grease to the bearings of the latter, and mounted in the chamber 55 is a plunger 57 which is adapted to be forced 45 against the lubricant by fluid pressure delivered to a space above the piston through a passage-way 58 leading from an annular channel 59 on the inner periphery of the head. The channel is normally closed by the sleeve 50 but is adapted to be opened to a port 60 in the stem 15 through a port 61 in the sleeve when the sleeve 50 is in its retracted position whereby the liquid in the stem will flow through the passage-way 58 and exert a pressure on the piston 57 and thereby act to discharge grease from the chamber 55 during the time the head is interconnected with the stem; the sleeve 50 serving to cut off the fluid pressure above the plunger when the head is out of its interconnected position.

Formed in the head are chambers 62 (see Figure 12) which communicates with the exhaust passage 47 and are provided for the purpose of receiving and containing the

water formed by the expansion of the exhausted compressed air, the chambers being fitted with removable plugs 63 to facilitate drainage of the chambers.

As a means for enabling the ready assembly and disassociation of the head and the parts carried thereby, the head is formed of a series of annular sections; there being an intermediate section A to which is secured by bolts 64 a bottom end section B; and a top 75 end section C with an associated subjacent section D secured to the upper face of the intermediate section A by bolts 65. The shanks of the tools are carried in the section B, and project into the section A with the 80 toothed rings located in recesses formed between the sections A and B. The fluid pressure operated mechanism is located in the section D with the piston rods extending into the section A to engage the tool shanks 85 through the latter; and the intake and exhaust ducts are formed in the sections C and D. The division lines between the sections A, B, C, and D are located so that when the sections are separated, ready access 90 may be had to the parts encased within the head.

In operation, the stem with the head engaged therewith is rotated in any desired manner, and the cutting tools are reciprocated by delivering compressed air from any suitable source and means of control through the intake conduit 31 to the tool operating mechanism, whereby the tools are reciprocated as the head rotates so as to effect a cutting action and form a circular bore. During the cutting action of the tools they are disposed with their cutting edges extending substantially radially of the head. As here shown the tools are not of sufficient 100 length to cut to the center of the bore, their length being limited because of the necessity of the tools being disposed entirely within the plane of the boundary of the head when in their inoperative position, as 105 indicated in dotted lines in Figure 10. Accordingly, as a means for removing the core formed in the bore at the inner ends of the cutting tool, a suitable cutter 66 is mounted on the end of the tubular stem, the cutter 110 embodying a plate 67 which is secured to the stem by bolts 68 and carries cutting elements of any desired design. The plate 67 is formed with openings 69 through which water may be delivered to the bore from the 115 tubular stem adjacent the cutting elements of the core cutter and the tools. The water delivered to the bore serves the purpose of carrying away the materials removed by the tool as is common in well drilling operations.

The weight of the head maintains it in position on the stem, and the latter is lowered as the cutting tools effect penetration.

It is to be observed that the fluid pressure 130

for operating the tools is conveyed to and from the fluid pressure operated mechanism in separate conduits, being exhausted to the atmosphere through conduit 32 which opens 5 to the atmosphere above the water in the stem, the exhaust air being thus enclosed off from the water in the stem and bore, so that the pressure of the latter will not interfere with operation of the fluid pressure 10 actuated mechanism.

When it becomes necessary to re-sharpen or replace the cutting tools a suitable tool is lowered into the bore on a cable operated by any suitable mechanism which tool is 15 adapted to engage the flange 34 on the head, so that on pulling the cable upward the head may be withdrawn from the bore without necessitating the removal of the stem and the air conduits. In a like manner, the head 20 may be restored to its operative position by lowering it into the well to its seated position on the end flange of the stem. After the head has been re-positioned on the stem, the tools engaging the flange 34 may be released therefrom in any suitable manner and withdrawn from the bore.

The head on moving in and out of its inter-connection with the stem, the cutting tools are turned to and from their operative 30 position; being disposed so as to extend within the space bounded by the plane of the periphery of the head and the periphery of the stem when the head is out of its inter-connected relation with the stem so that the 35 head may be freely raised and lowered; the tools being turned to extend diametrically or radially of the head, to project below the end of the stem and also extend beyond the plane of the periphery of the head as shown 40 in full lines in Figure 10, when the head is interconnected with the stem.

Stop pins 70 are provided on the end of the head to limit the inward turning movement of the blades 67 so as to insure the 45 teeth 40 being properly positioned to ride into engagement with the teeth 20 on the stem when the head is lowered. The collars 35 and scallops 18 serve as a means for guiding the teeth 40 into engagement with the 50 teeth 20 as the head cannot move to its seated position on the stem until the collars are positioned to enter the scallops and the teeth 40 can not engage the teeth 20 until the 55 collars are positioned to enter the scallops.

While we have shown and described a specific embodiment of the invention we do not limit ourselves to the exact details of construction disclosed but may employ such changes in the construction and arrangement 60 of the parts, and such modifications and equivalents, as come within the scope of the appended claims.

We claim:—

1. In a boring mechanism of the character described a stem, a head slidable on

said stem, means for interconnecting the head and stem, fluid pressure operated cutting tools on said head, means for conveying air to and from the lower portion of said stem enclosed off from liquid in the bore, means for affording communication between said air conveying means and said head when the head and stem are interconnected, and means for closing the air conveying means when the head is disposed out of 75 interconnection with the stem adapted to automatically open the communication when the head and stem are moved into interconnection.

2. In a bore forming mechanism, a stem, 80 a head slidable on said stem, means for interconnecting the head and stem, cutting tools on said head, fluid pressure operated mechanism in said head for actuating said tools, means for conveying air to and from the lower portion of said stem enclosed off 85 from liquid in the bore, ports on the stem and head adapted to register and afford communication between said air conveying means and the fluid pressure operated mechanism when the head and stem are interconnected, means for automatically closing said ports when the head and stem are out 90 of interconnection, and means operable on moving the head and stem into interconnection whereby said last named means will be actuated to open said ports.

3. In a bore forming mechanism, a stem, 95 a head slidable on said stem, means for interconnecting the head and stem, cutting tools on said head, fluid pressure operated mechanism in said head for actuating said tools, means for conveying air to and from the lower portion of said stem enclosed off 100 from liquid in the bore, ports on the stem and head adapted to register and afford communication between said air conveying means and the fluid pressure operated mechanism when the head and stem are interconnected, a valve carried by said stem for 105 normally closing the ports therein, a valve carried by said head for normally closing the ports in the head, and means whereby said valves will be positioned to open said 110 ports when the head and stem are moved 115 into interconnection.

4. In a bore forming mechanism, a stem, 120 a head slidable on said stem, means for interconnecting the head and stem, cutting tools on said head, fluid pressure operated mechanism in said head for actuating said tools, means for conveying air to and from the lower portion of said stem enclosed off 125 from liquid in the bore, ports on the stem and head adapted to register and afford communication between said air conveying means and the fluid pressure operated mechanism when the head and stem are interconnected, a slide valve carried on said stem 130 normally closing the ports in the stem, a

- slide valve carried by the head normally closing the ports therein; said slide valves being arranged in superposed relation and adapted to co-operate with each other to effect opening of the ports on moving the head and stem into interconnection. 5 and stem, a series of reciprocal and turnable tool shanks carried by said head, cutting 65 tools on said shanks, a toothed element having splined engagement with each of said shanks, means on said stem engageable with the toothed elements adapted to effect rotation of the latter on relative longitudinal 70 movement of the stem and head whereby the tool shanks will be turned as the head and stem move in and out of interconnection and adapted to hold the shanks against turning when the head and stem are interconnected, 75 spring means normally maintaining the shanks in their uppermost positions, and fluid pressure operated mechanism for effecting movement of said shank in opposition to said spring means. 80
5. In a well drilling mechanism, a stem having separated intake and exhaust chambers and formed with ports opening to the 10 side of the stem, means for delivering air under pressure to one of said chambers, means for conveying exhaust air from the other chamber opening to the atmosphere and enclosed off from liquid in the well, a 15 slide valve carried by said stem normally closing said ports, a tubular head slidably encompassing said stem, cutting tools carried by said head, fluid pressure operated mechanism for actuating said tools carried 20 by said head, ports in said head adapted to register with the ports in the stem, and a slide valve on said head normally closing said ports; the valves on the stem and head being adapted to coact with each other on 25 moving the head longitudinally of the stem in one direction to open said ports. 90
6. In a well drilling mechanism, a stem, a head slideable on said stem, means for interconnecting the head and stem on relative longitudinal movement thereof, a cutting tool turnably mounted on said head normally disposed within the plane of the boundary of said head, means operable to turn said tool on movement of the head and stem into interconnection to position said tool substantially radially of said head whereby the outer portion of the tool will project beyond the plane of the boundary of said head, and means for actuating said 10 tool by fluid pressure after it has been disposed in its radial position. 95
7. In a well drilling mechanism, the combination of a stem, a head surrounding said stem and adapted to be moved up and down thereon, means for interconnecting the head and stem, a series of reciprocal and turnable tool shanks carried by said head, cutting tools on said shanks, a toothed element having splined engagement with each of said 105 shanks, means on said stem engageable with the toothed elements adapted to effect rotation of the latter on relative longitudinal movement of the stem and head whereby the tool shanks will be turned as the head and stem move in and out of interconnection and adapted to hold the shanks against turning when the head and stem are interconnected, and means for reciprocating said shanks. 110
8. In a well drilling mechanism, the combination of a stem, a head surrounding said stem and adapted to be moved up and down thereon, means for interconnecting the head 115

9. In a drilling mechanism, a stem, a core cutter on the end of said stem, a head slideable on said stem, means for interconnecting the head on said stem, a plurality of cutting blades carried by said head, means for turning said blades in and out of a cutting position on moving said head in and out of connection with said stem, means for delivering water through said stem to said blades and core cutter, pressure operated mechanism for actuating said blades, and means for delivering air under pressure to said pressure operating mechanism through said stem apart from the water therein. 90

10. In a drilling mechanism, a stem, a head adapted to be mounted upon said stem formed of a series of superimposed detachably connected sections, a series of cutting tools mounted on the lower end section, an intermediate section to which the lower end section is attached, compressed air mechanism carried in a section adjacent to the intermediate section operating through the latter to actuate the drill mechanism, and an upper end section, and means for passing air through said upper end section from interiorly of the stem to effect operation of the drill operating mechanism. 100

11. In a well drilling tool, a head comprising a series of superimposed detachably connected annular sections; there being an intermediate section, a bottom end section affixed to said intermediate section, a top section and an adjacent section secured to said intermediate section; a series of reciprocal cutting tools carried by the bottom end section, fluid pressure operated mechanism carried by the top and its adjacent section for actuating said tools through the intermediate section, and means for delivering compressed air to said mechanism through said top section. 115
